Attorney

UNITED STATES PATENT OFFICE.

CLARENCE W. CLEMENTZ, OF JACKSONVILLE, FLORIDA, ASSIGNOR TO CRANKLESS ENGINE COMPANY, OF JACKSONVILLE, FLORIDA, A CORPORATION OF FLORIDA.

SPRAY VALVE.

Application filed August 17, 1922. Serial No. 532,566.

To all whom it may concern:

Be it known that I, CLARENCE W. CLEMENTZ, a citizen of the United States, residing at Jacksonville, in the county of Duval and State of Florida, have invented certain new and useful Improvements in Spray Valves, of which the following is a specification.

My said invention relates to a spray valve for internal combustion engines and it is an object thereof to provide a valve in which the fuel shall be in condition to give a fine spray at the instant that the valve is opened. One defect in devices of this sort has been that the fuel is not sprayed properly at the instant of opening the valve, due to lack of pressure or to inertia. This condition causes improper and wasteful combustion of the fuel, together with accumulation of carbon.

A further object of the invention is to provide a device of this character which shall be simple and economical to manufacture, being composed of few and simple parts. This also enables the device to be quickly and easily repaired without undue expense.

25 The single drawing shows a vertical section of the device in position on a cylinder.

In the drawing reference character 10 indicates a cylinder of conventional type having an opening 11 in which the lower portion of the valve is situated. The spray valve housing 12 has a flange extending over the opening and secured in place by bolts or other conventional means. At its lower end the housing partially encloses a valve casing 13 having a flange 14 extending between the cylinder and the flange of the body member. A packing 15 is situated between the cylinder and the flange 14. The valve casing has a fuel inlet at 16 leading to a longitudinal passage 17, which extends from end to end of the casing. The casing has a central valve chamber closed at one end by a gland 18 and having located therein a pair of bushings 19 and 20, which may be held in place by having a driving fit, or by other known means.

It will be noted that the external diameter of the lower bushing is the same as that of the lower flange of the upper bushing. At the lower end of the casing is a conical casing head 21 held in place by the spray tip 22 having screw-threaded engagement with the end of the casing and holding the casing head in place. The spray tip has a perforation 23 tapering at both ends and communi-

cating with radial channels 24 at the lower side of the casing head.

The channels 24 extend radially of the head and then upwardly through it, opening near the periphery of a chamber 25 beneath bushing 20, which chamber is in communication with the passage 17. A chamber 26 between the bushings also communicates with said passage.

A valve 27 is slidably mounted in the bushings 19 and 20, the portion of the valve in bushing 19 being of smaller diameter than that in bushing 20, thus forming an upwardly facing ledge in the chamber 26. At its lower end the valve has a tip 28 ending in a tapering formation adapted to close off the passages 24. The tip 28 is considerably smaller than the valve section in bushing 19, thus leaving a downwardly facing ledge at the upper end of the tip in the chamber 25 of larger surface than the similar face in the chamber 26.

A tappet 29 is pivoted at 30 on the body 12 and has a rounded face engaging a nut 31 held in place by lock-nut 32 on a stem 33 adapted to contact with the upper end of the valve 27. The stem is normally held down by a spring 34 bearing at its upper end against a shoulder 35 on sleeve 36. This sleeve is loosely mounted in an opening of the housing 12 and its position is determined by adjustment of a cap 37. At the lower end of the stem 33 is a leak-off passage 38 communicating with a chamber 39 surrounding the lower end of the stem and the upper end of the valve 27. This provides for escape of such small amount of oil as may leak by the valve and the bushings 19 and 20, which have a minute clearance (.0001 in.) and are not packed.

In the operation of my device, the stem 33 is moved up and down by tappet 29 in the usual manner. The fuel in the passage 17, chamber 25 and communicating passages in head 21 is under heavy pressure as usual, and such pressure may build up, if desired, while the valve is closed, or may be substantially constant. After the stem 33 is raised, the valve 27 will be raised by the differential pressure on the oppositely facing ledges in chambers 25 and 26. The proportions of the parts are such that the ledge in chamber 25 is spaced from head 21 even when the valve is closed, thus permitting the oil pres-

sure to open the valve, as above set forth. The pressure on the fluid being high the valve will immediately be raised when the pressure of the stem is removed therefrom and the tip 28 will be withdrawn from the spray valve passage 23, thus opening communication between the fuel passages and the cylinder.

Having fully described my invention, what I claim as new and desire to secure by Letters Patent, is:

1. A spray valve comprising a valve casing having a longitudinal fuel passage and a valve chamber, a valve in the chamber having a central enlarged portion and being reduced at its ends, a bushing about the enlarged portion, a bushing about the upper reduced portion spaced from the first to form a pressure chamber and coacting with the end of the enlarged portion to form a stop for the valve, a head surrounding the lower reduced portion and providing a pressure chamber between it and the lower bushing, a spray tip, and passages leading from the main fuel passage to each of said chambers, and also through the head to the spray tip, substantially as set forth.

2. In a spray valve for internal combustion engines, a cylindrical valve casing having an annular flange, a housing surrounding the casing and its flange and adapted to be secured to the engine, a valve in the casing having a central enlargement said casing having an inner bore divided by circumfer-

ential shoulders into parts of different diameter, bearing means interposed between the casing and the valve and providing differential pressure chambers adjacent said shoulders, and a removable spray tip at the foot of the casing providing for the removal of the bearing means, substantially as set forth.

3. In a spray valve for internal combustion engines, a cylindrical valve casing having an annular flange, a housing surrounding the casing and its flange and adapted to be secured to the engine, a valve in the casing having a central enlargement said casing having an inner bore divided by circumferential shoulders into parts of different diameter, bearing means interposed between the casing and the valve and providing differential pressure chambers adjacent said shoulders, a removable conical casing head surrounding the lower reduced end of the valve, and a removable spray tip at the foot of the casing providing for the removal of the other parts from the casing, substantially as set forth.

In witness whereof, I have hereunto set my hand at Jacksonville, Florida, this 12th day of August, A. D. nineteen hundred and twenty-two.

CLARENCE W. CLEMENTZ.
